HOSIERY TURNING AND INSPECTING FORM

Filed Sept. 4, 1929

INVENTOR:
Hugo Hemmerich,
BY *W.G. & D. Stewart*
ATTORNEYS.

UNITED STATES PATENT OFFICE

HUGO HEMMERICH, OF WYOMISSING, PENNSYLVANIA, ASSIGNOR TO BERKSHIRE KNITTING MILLS, OF WYOMISSING, PENNSYLVANIA, A CORPORATION OF PENNSYLVANIA

HOSIERY TURNING AND INSPECTING FORM

Application filed September 4, 1929. Serial No. 390,227.

The present invention relates to forms for use in the turning and inspection of tubular garments such as stockings. The invention is a development of that disclosed in my prior Patent No. 1,750,005, of March 11, 1930, and has for an object to improve the construction of the device therein disclosed in a manner such that a thorough inspection of a garment of the character referred to 10 may be facilitated.

To this end the form, instead of being comprised of an integral unitary member as in the above copending application, is comprised of two sections so that the form 15 may be expanded; the entire form considered as a unit being rotatably mounted upon a suitable support. The form has associated therewith suitable mechanism for expanding the same and operating mechanism connected with the expanding mechanism so as to permit of relative rotation therebetween.

For a full understanding of the invention reference is made to the accompanying drawings, and the novel features are clearly 25 defined in the subjoined claims.

Fig. 1 is a longitudinal section through the form, showing the mounting thereof, the expanding mechanism and the connection of the operating mechanism therewith.

Fig. 2 is a cross section through the form on line 2—2 of Fig. 1, showing the form unexpanded.

Fig. 3 is a similar view to Fig. 2 showing the form expanded.

The forms employed in inspecting stockings are usually stationarily mounted and are incapable of expanding the garment further than that initially effected by drawing the same on to the form. The forms 35 being stationary the inspection of all parts of the garment are not of equal thoroughness. The present invention overcomes this difficulty and is particularly adapted to facilitate the inspection of the seam in full 40 fashioned stockings where the faults in construction are particularly hard to detect in addition to the qualities which constitute the above named copending invention an advance over prior art.

50 In the embodiment shown in the draw-

ings, 10 designates a form of a shape suitable to facilitate stringing of a stocking thereon, the same being mounted for rotation, relative to a suitable support which may be, as shown in the nature of a bracket 55 11 suspending the form from a table 12. The form is comprised of sections 13 and 14 mounted for relative movement one to the other so as to expand the form with a consequent stretching of a garment strung 60 thereon.

The mounting of the sections to this end may be of any suitable character but should be secured against relative longitudinal movement and to this end they are connected to each other along one edge of the adjacent faces by hinges 15.

The sections are further connected by suitable expanding mechanism which may be in the nature of a rod 16 slidably longitudinally of the form which is provided for the accommodation thereof with an axial bore 17. This rod is slidably connected with one of the sections as section 13 which is provided to this end with lugs 18 having 70 75 aligned openings therethrough.

The rod 16 is connected to the section 14 by a plurality of links 19, pivoted to collars 20 on the rods and to lugs or ears 21 formed on this section.

The rod 16 is rotatably supported in a sleeve 22 which extends through a bore 23 formed in the bracket 11; the sleeve being held against rotation by a set screw 24. The form is also rotatably connected with this 85 sleeve which projects a distance into the bore 17 thereof; the rotatable connection being effected through anti-friction bearings 25 the races of which are respectively secured to sleeve 22 and a sleeve 26 secured to section 90 13 of the form.

The rod 16 is given its longitudinal movement through operative mechanism connected therewith at one end which projects beyond the bracket 11 and is connected therewith for relative rotation as by a universal joint 27.

The operating mechanism may be of any suitable character, as a foot treadle 28 fulcrumed at 29 upon the floor and pivoted to 100

a link 30, at one end; the other end of the link being connected to one arm 31 of the bell crank 32 pivoted at 33 to a bracket 34 by which it is suspended from the table 12; the other arm 35 of the bell crank being pivoted to the link 36 constituting a part of the universal joint.

The rod 16 is normally held in form collapsing position by means of a tension spring 37 connected between lugs 38 and 39 respectively on the table 12 and arm 31 of the bell crank lever.

By the relationship of the mechanism as herein described the form 10 is maintained normally collapsed and may be expanded by pressure exerted on the treadle 28. The form being rotatable on the sleeve 22 independently of the collapsed or expanded condition of the form, both collapsing and expanding being positively effected through the connection between the rod 16 and the sections of the form.

The expansion of the form is an angular movement of one section relative to the other, providing a gap or recess extending the full length of the form and this fact may be taken advantage of in the inspection of the seam in full fashioned stockings which may, by proper manipulation, be positioned over the said gap or recess.

The form has in common with the invention of my copending application the opening 40 adjacent one end and the recess 41 communicating therewith to facilitate reversing of a stocking which in both cases is placed on the form by extending the stocking through this opening garter end first and then drawing the same to the right over the form. The stocking being thus mounted on the form, the same may be expanded to any degree desired by exerting the required pressure on the treadle 28.

What I claim is:

1. An inspecting form for use with tubular garments comprising two sections mounted for relative lateral movement, one of said sections having a member slidably connected therewith, and links connecting the other section to the said member, said sections being hinged together along one side.

2. An inspecting form for use with tubular garments comprising a substantially cylindrical member rotatably supported and divided longitudinally into sections hinged together along one edge of adjacent surfaces thereof, a rod connected with one section for relative longitudinal movement and with the other for relative radial movement, a treadle for moving said rod, and means connecting said treadle to said rod so as to permit relative rotation therebetween.

3. An inspection form for use with tubular garments, comprising a plurality of sections pivotally connected longitudinally,

and internal expanding means adapted to diametrically spread said sections.

4. An inspection form for use with tubular garments, comprising a plurality of sections pivotally connected longitudinally and mounted for joint rotation about a common longitudinal axis, and internal expanding means having an external operating extension adapted to diametrically spread said sections during their joint rotation.

5. An inspection form for use with tubular garments, comprising a plurality of sections pivotally connected longitudinally, and internal expanding means comprising a longitudinally shiftable rod with section-connected links adapted to diametrically spread said sections.

6. An inspection form for use with tubular garments, comprising a substantially cylindrical form longitudinally divided into a plurality of sections, hinges pivotally connecting the edges of adjoining sections, and internal expansion means adapted to diametrically spread said sections by pivotally swinging said sections on their hinges.

7. An inspection form for use with tubular garments, comprising a substantially cylindrical form longitudinally divided into a plurality of sections and mounted for joint rotation upon their common longitudinal axis, hinges pivotally connecting the edges of adjoining sections, a longitudinally shiftable rod extending into and internally mounted in one of said sections, links connecting said rod to the other section, and external means for longitudinally shifting said rod during rotation of said form to diametrically spread said sections by pivotally moving them on their hinge connections.

In testimony whereof I affix my signature.

HUGO HEMMERICH.
